UNITED STATES PATENT OFFICE

2,596,443

METHOD OF PICKING FOWL

Allen W. Sharp, Ottumwa, Iowa, assignor to
 Barker Poultry Equipment Company, Ottumwa,
 Iowa, a corporation of Iowa

Original application June 4, 1947, Serial No.
 752,314. Divided and this application April 23,
 1949, Serial No. 89,209

5 Claims. (Cl. 17—45)

1

This application is a division of my copending application, Serial No. 752,314, filed June 4, 1947.

The present invention relates to a method of picking fowl.

A serious objection to previous methods of picking fowls is that it was practically impossible, by the use thereof, to pick all of the feathers from the fowls. It was formerly customary to suspend fowls on a moving overhead conveyor, and at a point along the line of travel a picker operated on the fowls, sweeping downwardly thereover. There were certain parts of the fowls which were not completely picked, such as the back of the wings, back, etc. Those parts of the fowls were not in position where the picker could strike the feathers.

It was then customary to finish the picking process by hand operation. The picking operation could be carried further by mechanical means by reversing the fowls on the conveyor, and subjecting them again to a picker. Such reversal of the fowls involved the expensive hand operation of reversing the fowls.

I conceived the idea that, instead of reversing the fowls on the conveyor for a second operation, the picking operation could be reversed, resulting in greater efficiency and economy. Various difficulties were of course encountered, the chief one being that if the picking mechanism swept upwardly over the fowls suspended from an overhead conveyor, the fowls would be carried upwardly and dangle above the picking mechanism.

I next conceived the idea of holding the heads of the fowls down for the up-sweeping picking operation.

It is therefore an object of the present invention to provide a method of picking fowls which comprises the steps of supporting the fowls in depending position, holding the lower ends of the fowls against upward movement, and picking the fowls.

Another object is the provision of a method of picking fowls, of the nature above referred to, which can readily be employed in conjunction with conventional picking methods heretofore known, whereby substantially all of the feathers are picked from the fowls.

Still another object is the provision of a method of picking fowls, of the nature above referred to, in which the picking operation is intermittent.

A further object is the provision of a method of picking fowls, of the nature above referred to, in which the picking operation takes effect on the fowls progressively from one end of the fowls to the other, and then is reversed.

2

With these and other objects in view, this invention consists in the method as hereinafter more fully set forth, pointed out in the claims herein, and embodied in the operation of the device illustrated in the accompanying drawings, wherein:

Figure 1 is an end view of a machine designed for carrying out the present invention;

Figure 2 is a side view, as viewed from the right 10 of Figure 1;

Figure 3 is a top view;

Figure 4 is an enlarged sectional view taken on line 4—4 of Figure 3;

Figure 5 is a partial view taken on line 5—5 of 15 Figure 1;

Figure 6 is a partial view taken on line 6—6 of Figure 3;

Figure 7 is a detail view of the center of one of the chicken picking drums;

Figure 8 is a view, on a reduced scale, taken on 20 line 8—8 of Figure 7;

Figure 9 is a reduced diagrammatic illustration showing the different positions of adjustment of the head holding means;

Figure 10 is a diagrammatic view showing various 25 positions of the chicken picking drums; and

Figure 11 is a diagrammatic view illustrating the hydraulic control mechanism for operating the chicken picking means.

Referring now in detail to the drawings, the 30 device includes a main frame 12 having an end unit at each end of the machine, each end unit comprising inner upright members 14, horizontal members 16, and other reinforcing and strengthening members 18. The two end units are inter-

35 connected by longitudinal members 19. The mechanism is to be used in connection with a conveyor indicated generally at 20 from which fowls are suspended. The conveyor is provided with customary driving means, and travels longitudinally through the machine from left to right as illustrated in Figure 2. The frame end units are secured together at the top by means of yokes 22, one at each end of the frame, which are removably secured in the upper ends of the respective upright members 14. The yokes 22 are placed in position after adjusting the machine with relation to the conveyor 20, since the conveyor may be designed for other machinery. The apparatus may be supported on adjustable legs 24 to compensate for unevenness in the supporting floor.

40 A fowl is indicated at 26 in Figure 1, supported by a shackle 28 which may be of any convenient type. Shackles 28 are spaced at con-

45

venient intervals along the conveyor, as indicated in Figure 2.

The fowl 26 is shown suspended by the feet with the head down, as is customary in chicken picking operations. As explained above, previous chicken pickers swept downwardly over the fowls and in order to sweep upwardly it is necessary to secure their heads and retain them from rising upwardly. To this end a head holding means is provided for engaging the heads of the fowls and retaining them down.

The head holding means is indicated as a whole at 30, and includes a pair of longitudinal members or shields 32, having inturned flat portions 34 and 35 (Figure 4). The flat portion 34 may be secured to the respective shield 32, but the portion 35 is separate from its shield 32 for adjustment purposes, as will be pointed out later. The shields 32 form an inverted trough, that is, their sides are inclined outwardly and downwardly, and are supported by longitudinal reinforcing tubular members 36. The shields 32 are spaced apart so that the upper flat portions 34 and 35 form a longitudinal open channel 38, and depending from the under surfaces of the flat portions 34 and 35 are backing plates 40 which extend downwardly a short distance and reach longitudinally substantially the full length of the head holding means. It will be noted that the head holding means 30 extends entirely through the machine.

The shields 32 are supported in relative positions, and the head holder frame rendered unitary, by cross pieces 42 at each end to which the tubular members 36 are secured (Figures 5 and 6). Extending longitudinally beyond the tubular members 36 at each end of the head holder frame are additional members 43 to the ends of which are secured cross pieces 44. At the entering end of the machine (the left of Figure 3) vertical bearing members 45 are interposed at the juncture between the members 43 and the cross pieces 44, but at the exit end, the bearing members 45 may be omitted.

Secured to each cross piece 42, as by welding, are a pair of plates 46, spaced apart relative to each other, and extending upwardly and outwardly from the cross pieces.

The upper portions of the plates 46 are turned over horizontally, and secured to the outer extremities of the upper flat portions of the plates 46 are brackets 47 which in turn support collar elements 48. The collar elements 48 are adapted to slidably engage the upright members 14 of the main frame 12 for vertical adjustment of the head holder frame 30.

Hoods 49 and 49' are secured to the ends of the flat portions 34 and 35 of the shields 32. The hoods 49 and 49' at each end of the head holding frame are spaced apart from each other, similarly to the plates 46, and have portions extending horizontally, and downwardly.

A pair of chains 50 are arranged in the head holding means below the flat portions 34 and 35 of the shields 32 so that each chain has a run 51 on the inside of the respective backing plate 40, and a run 52 on the outside thereof. The chains 50 may be conventional sprocket chains. If desired, horizontal supporting ledges such as 53 may be provided for supporting the chains 50 upwardly.

A pair of driving sprockets 54 are supported by shafts 55 and 56 in the vertical bearing members 45 at the entering end of the head holder 30, one sprocket being on each side of the open

channel 38, over which respective chains 50 are trained. The sprockets 54 are operated by meshing gears 57 and 58 secured to the lower ends of the shafts 55 and 56 below the respective cross piece 44. The cross pieces 44 are disposed a considerable distance below the flat portions 34 and 35 of the shields 32 to provide space for the heads of the fowls, as will be explained more fully later. Idler sprockets 59 are provided adjacent the driving sprockets 54 to guide the outer runs 52 around the driving sprockets 54. The idler sprockets 59 may be journaled in the horizontal portions of the hoods 49 and 49'; the hoods 49 and 49' may have bearing support on the upper ends of the shafts 55 and 56, if desired; a slot 60 is provided in the hood 49' to accommodate the shaft 56.

The opposite or exit end of the head holder 30, shown at the right of Figure 3, is provided with cooperating sprockets 61 and corresponding idler sprockets 62, both of which may be supported by the respective hoods 49 and 49'. Additional shields 63 may be provided at the ends of all of the hoods 49 and 49'.

The width of the open channel 38 in the head holding means 30 may be adjusted within limits. An adjusting screw 64 is threaded in a bracket 66 fixed on the plate 46 adjacent the hood 49' at each end of the machine. The screws 64 have operable connection with the vertical portions of the hoods 49', and by adjusting the screws, the hoods 49' and the interconnecting flat portion 35 of the adjacent shield 32 can be adjusted in and out. This movement carries the respective backing plate 40 and the corresponding runs 51 and 52 of the chain toward and away from the opposite backing plate and chain. Although the sprocket 54 remains fixed, and the sprockets 59, 61 and 62 move with the hoods 49', the movement of the hoods 49' is so small that the tension of the chain 50 on that side of the head holder means is not materially effected. The distance between the runs 51 of the chains is determined by the sizes of the necks of the fowls passing through the machine. The extent of adjustment of the channel 38 need not be great, only enough to accommodate the different sizes of necks of the fowls.

Drive for the chains 50 is provided by a motor 67 at the entering end of the head holder 30 and supported on one side thereof by the respective hood 49. A drive pulley 68 on the motor 67 by means of belt 69 drives a gear box 70 having a drive gear 72 which meshes with the gear 57. It will thus be seen that both chains 50 are driven by the motor 67, through meshing gears 57 and 58.

Secured to each of the plates 46, as by means of brackets 71 at each end of the head holder 30 and on each side of the center thereof is a guide frame 73. The guide frames 73 are in the form of plates disposed transversely of the machine.

Each guide frame 73 includes a slot 80, the upper major portion of which is vertical as indicated at 82. The lower portion of each slot 80, as indicated at 84, is angled outwardly and downwardly parallel to the inclination of the shields 32 of the head holder 30. The upper and lower ends of the guide frames 73 are provided with bearing collars 86 slidably fitted on the upright members 14. The bearing collars 86 on the guide frames 73, and the collar elements 48 on the plates 46, are adapted to slide

along the upright members 14 for vertical adjustment of the head holding means 30.

A winch indicated at 90 is supported on the main frame 12 for vertical adjustment of the head holding means 30. One flexible cable indicated at 92 leads directly from the winch to the adjacent side of the head holding means 30 (Figure 1), and a second flexible cable 94 leads downwardly, across the main frame, and to the opposite side of the machine, where it then leads upwardly and is trained over a pulley and connected to the head holding means at the opposite side of the machine. Thus the central portion of the machine is kept clear for the passage of fowls therethrough. The cables 92 and 94 are secured to the outer ends of plates 46 which in turn are secured on the head holding means 30. The winch 90 is secured on a shaft 98 extending longitudinally of the machine, and on the opposite end a similar arrangement of winch and cables is provided for the opposite end of the head holding means 30. By operation of the winches 90 the head holding means 30 may be raised and lowered. The guide frames 16, being fixedly secured to the head holding means 30, are raised and lowered with the head holding means.

The picking means includes a pair of rotatable drums 100 disposed on axes positioned longitudinally of the machine. The construction of the drums 100 may be observed from Figures 7 and 8. Each drum 100 includes a shaft 102 upon which is mounted a frame-work 104 including a plurality of axially extending plates 106. Each plate 106 is provided with a series of notches 108. The notches 108 are V-shaped at their outer ends, and their inner ends are rounded for insertion of flexible picking fingers 110. The fingers 110 are inserted in the notches 108 and when so inserted are securely held in place therein by friction. Rotation of the drum is preferably as indicated by the arrow in Figure 8 so that the picking fingers 110 are more easily retained in the notches.

The picking fingers 110 are preferably long and flexible. When the drum is stationary, the fingers 110 are flexible enough to hang, and the outstretched position of the fingers in Figure 8 indicates rotation. The fingers 110 also preferably are provided with circumferential ribs. The representation of the drums 100 in Figures 1, 2 and 3 is semi-diagrammatic; they are shown only in the outline of the extremities of the fingers 110 when in rotation.

Each drum 100 is supported by a framework including an upright arm 112 pivoted at 114 on the lower transverse frame member 16. One such arm 112 is provided at each end of the machine for each drum. A longitudinal shaft or bar 16 is pivoted in the upper swinging ends of the respective arms 112. Rigidly secured to each end of the longitudinal shaft 116 is a second swinging arm 118. In the outer ends of the arms 118 are bearing members 120 for supporting the ends of the shaft 102 of the respective picking drum 100. Outwardly of the bearing members 120 are enlarged extensions 122 fixed to the shaft 102 and adapted to extend into and slide in the guide slots 80.

The drums 100 are adapted to be raised and lowered and be guided by the slots 80 as will be more fully explained later. The means for raising and lowering the drums 100 consist of a hydraulic ram 124. One such ram 124 is provided for each drum, and is pivoted on an arm 125 on

the frame 12. The present illustration shows the rams 124 pivoted adjacent the pivot points 114 of the arms 112, but this may be varied if desired. Since the arms 118 are rigidly secured to the longitudinal member 116 they form a rigid framework, and the hydraulic ram 124 being disposed only at one end thereof is effective for raising and lowering the arms 118 at both ends, and thereby prevent binding of the drum 100 in its movements.

The frame-work for supporting the drums 100 is provided with appropriate reinforcing members such as vertical plates 126 to which the rams 124 may be secured, and a horizontal plate 128. A drive motor 130 is supported on the horizontal plate 128 and has appropriate drive by means of a belt 132 to the picking drum 100. One such drive motor 130 is provided for each picking drum 100. As the picking drum 100 is raised and lowered the drive motor 130 is carried therewith.

The raising and lowering of the picking drums 100 is effected automatically. Gear 58 is provided with downwardly extending pins 134 which on rotation of the gear 58 engage a trip lever 136 in a valve operating device 138 carried by the head holding means 30. On one side of the machine one of the swinging arms 118 which supports the drum 100 has secured thereto a plate 139 upon which is mounted a vertically adjustable pin 140 adapted to engage a trip lever 142 in a second valve operating device 144. The pins 134 are adapted to actuate the hydraulic drive so that the rams 124 are extended, and the pin 140 is operable to reverse the action of the hydraulic drive when the picking drums 100 reach the desired height. The height to which the drums 100 are raised can be controlled by adjusting the pin 140 to different heights.

Figure 11 shows diagrammatically one form of hydraulic mechanism for actuating the hydraulic rams 124. A pump and reservoir is indicated at 146 having leads 148 to the rams 124. As the gear 58 rotates, the pins 134 engage the trip lever 136 operating a valve which actuates the hydraulic system to extend the hydraulic rams 124. After the drums 100 reach the desired height, the pin 140 on the arm 118 engages the trip lever 142 and reverses the hydraulic drive so that the picking drums 100 descend. The particular kind of hydraulic drive does not form an essential part of the present invention, and any desired drive may be used. For example the picking drums 100 may be permitted to descend of their own weight; or they may be lowered positively.

Practical operation

The head holding means 30 is adjusted to an appropriate height to accommodate fowls of the particular sizes being treated. Fowls vary in size from one to the next, and of course different kinds of fowls are of different sizes. One customary type of classification, for which convenient adjustment of the machine may be made, is recognized as—little chickens, big chickens, little turkeys, and big turkeys.

Figures 1 and 4 illustrate a fowl which is small compared with the present position of adjustment of the head holding means 30. That is, the head of the fowl is just below the inner runs 51 of the chains 50. The dotted line position of the head of the fowl in Figure 4 indicates a larger fowl, and in such a case the head depends considerably below the chains 50. As the fowls travel along the conveyor the necks pass

through the open channel 38 in the head holding means. The picking drums 100 rotate in the direction indicated by the arrows in Figure 1, the picking fingers 100 sweeping upwardly over the fowls. The inner runs 51 of the chains 50 are adjusted so that they do not bear heavily on the necks of the fowls, but are at such spacing that the heads of the fowls cannot move upwardly between the chains. As the picking drums sweep upwardly on the fowls they are 10 prevented from being raised and tossed.

In the case of large fowls from which the heads depend substantially below the chains 50, the picking drums 100 in their upsweep operation carry the fowls upwardly to a point where 15 the head engages the chains 50. Such large fowls then actually float between the head holding means and the conveyor and the entire neck is exposed to the picking operation.

Figure 9 shows diagrammatically different positions of vertical adjustment of the head holding means 30. It will be noted that considerable range is provided to accommodate different sizes of fowls. It will also be noted that for any one position of adjustment a considerable range is 20 provided for different sizes of fowls, as evidenced by the space between the chains 50 and the gears 57 and 58.

In the picking operation it is desirable that the picking process is not constant but preferably intermittent. Hence the provision for raising and lowering the picking drums 100. It is also desirable that in such intermittent picking, the drums move bodily upwardly and downwardly over the fowls to provide a more thorough picking process. As the rams 124 are extended, the picking drums 100 are elevated and guided by slots 80. The upper portions 82 of the slots 80 are vertical as explained above, and guide the picking drums upwardly and downwardly over the fowls. As the picking drums 100 descend from the portions 82 of the slots, they are guided outwardly and downwardly by the lower portions 84 of the slots 80, so that the drums are withdrawn from the fowls and guided away from the head holding means 30.

The objective of the means for providing intermittent picking is that the drums come into and out of engagement with the fowls. Such action in conventional pickers is accomplished by having the picking means raised and lowered along the fowls, and to come out of engagement with the fowls by continuing the downward movement beyond the lower extremities of the fowls. In the present case after the picking drums are lowered to the lower ends of the fowls they are separated, and spread away from the center of the machine to avoid striking the head holding means.

It will be noted from Figure 1 that the extremities of the picking fingers 110 on the two drums 100 intermesh somewhat to assure that as much of the surface of the fowls as possible will be covered.

It is obvious of course that the speed of the chains 50 in the head holding means 30 is the same as the overhead conveyor.

Cycles of movement of the picking drums in their up and down movement can be regulated so that the fowls will be subjected to the picking process several times during their travel through the machine. It has been found that two or three times is the most effective for completely picking the fowls. This number may of course be varied to suit circumstances.

The machine herein described is preferably intended to be used in conjunction with a picking machine heretofore known, in which the picking fingers sweep downwardly over the fowls. In such an operation of sweeping downwardly over the fowls, many of the feathers are removed, but as pointed out above, there are certain parts of the fowls that are not reached by the picking fingers. After the fowls have been subjected to the down sweeping operation, they are then subjected to the picking operation disclosed herein, and substantially all of the remaining feathers are thereby removed.

While I have herein disclosed a preferred embodiment of my invention, manifestly it is susceptible of modification without departing from the spirit and scope thereof. I do not therefore wish to be understood as limiting my invention to the precise form herein disclosed, except as I may be so limited by the appended claims.

I claim as my invention:

1. A method of picking fowls comprising the steps of suspending the fowl with their heads down, conveying the fowl when so suspended, guiding the neck of the fowl to a point where it is automatically and loosely seized for conveyance, whereby the neck and head of the fowl hang vertically downward, conveying the suspended fowl with the loosely seized neck, applying a picking force upwardly over the fowl, whereby the body of the fowl tends to be thrown upwards, and the step of engaging the head of the fowl during the picking operation to restrain the body of the fowl from being thrown upwards by the picking force.

2. A method of picking fowls comprising the steps of suspending the fowl with their heads down, conveying the fowl when so suspended, guiding the neck of the fowl to a point where it is automatically and loosely seized for conveyance, whereby the neck and head of the fowl hang vertically downward, conveying the suspended fowl with the loosely seized neck, intermittently applying a picking force upwardly over the fowl, whereby the body of the fowl tends to be thrown upwards, and the step of engaging the head of the fowl during the picking operation to restrain the body of the fowl from being thrown upwards by the picking force.

3. A method of picking fowls comprising the steps of suspending the fowl with their heads down, conveying the fowl when so suspended, guiding the neck of the fowl to a point where it is automatically and loosely seized for conveyance, whereby the neck and head of the fowl hang vertically downward, conveying the suspended fowl with the loosely seized neck, applying a picking force upwardly over a portion of the body of the fowl, whereby the body of the fowl tends to be thrown upwards, and the step of engaging the head of the fowl during the picking operation to restrain the body of the fowl from being thrown upwards by the picking force.

4. A method of picking fowls comprising the steps of suspending the fowl with their heads down, conveying the fowl when so suspended, guiding the neck of the fowl to a point where it is automatically and loosely seized for conveyance, whereby the neck and head of the fowl hang vertically downward, conveying the suspended fowl with the loosely seized neck, applying a picking force upwardly over a portion of the body of the fowl, moving said picking force upwardly and downwardly over the body of the fowl, whereby the body of the fowl tends to be

thrown upwards, and the step of restraining the downward end of the fowl from being thrown upwards by the picking force.

5. A method of picking fowls comprising the steps of suspending the fowls with their heads down, conveying the fowl when so suspended, guiding the neck of the fowl to a point where it is automatically and loosely seized for conveyance, whereby the neck and head of the fowl hang vertically downward, conveying the suspended fowl with the loosely seized neck, applying a picking force upwardly over a portion of the body of the fowl, moving said picking force over the body of the fowl from one end of the fowl to the other end and then reversing the 15 motion, whereby the body of the fowl tends to be thrown upwards, and the step of engaging the head of the fowl during the picking operation to

restrain the body of the fowl from being thrown upwards by the picking force.
